PROCESS OF RAISING THE CALORIFIC
VALUE OF LIQUID FUEL

Alexander Classen, Aachen, Germany

No Drawing. Application February 21, 1933,
Serial No. 657,845. In Germany July 30, 1932

2 Claims. (Cl. 44—9)

Attempts have been made for a long time to disperse coal in petroleum, so as to obtain a stable suspension which can be used as a fuel instead of pure petroleum. Apart from the fact that up to now it has been practically impossible to make mixtures in which the coal would not rapidly deposit, the use of coal for the said purpose has big disadvantages. First of all, it must be mentioned that coal contains considerable amounts of ash producing substances, which produces difficulties when petroleum-coal mixtures are used in the usual machines designed for pure petroleum firing.

It is now found that the calorific value of liquid fuels can be raised in an appreciably better fashion if products rich in carbon and obtained from wood are incorporated in them in a finely divided state. In this way, stable suspensions are obtained together with a series of other important advantages. Among the latter are to be found the fact that products rich in carbon and obtained from wood produce little or no ash and, as a consequence, burn without leaving a residue; by mixing the added materials in accordance with the invention, practically no increase in volume is obtained; lastly, the use of fuels made in accordance with the invention brings about an extraordinary cheapening of the relatively costly liquid fuels.

In addition to finely divided coal, lignin which is obtained in large quantities in the known processes for the saccharification of wood as well as in processes for obtaining furfural from materials containing cellulose can also be used as an additional substance. This lignin, which remains as a finely divided insoluble powder, when, for example, the cellulose is dissolved in highly concentrated hydrochloric acid to an amount of 25-30% according to the nature of the starting materials used, was hitherto hardly usable. Its use for the purpose in question here thus solves two problems at the same time.

In addition to the products rich in carbon and obtained from wood which have already been mentioned, finely divided, more or less pure amorphous carbon can also be dispersed in fuels, which leads to a particularly important increase in the calorific value of the fuel obtained. Lignin may, for example, be used for obtaining the amorphous carbon and for this purpose be treated in the following fashion.

The lignin obtained, for example, in the mentioned process for the saccharification of wood is washed with water, dried at about 100° and is subjected to dry distillation at a low temperature.

Combustible gases are given off which can be used for various purposes and if desired can be used as sources of heat for the dis-integrating process. A residue is produced which is a loose, porous mass consisting of amorphous carbon.

Instead of lignin, other organic materials rich in carbon and preferably of high molecular weight, for example, organic acids or substances of high molecular weight derived from them such, for instance, as glucose obtained in the saccharification of wood and in certain cases cane sugar or molasses can be treated in a similar fashion to produce the amorphous carbon.

The carbon obtained can be easily very finely subdivided and in this form suspended in liquid fuels without giving rise to any separation especially at low temperatures. It will be understood that several of the above mentioned products rich in carbon can be suspended at the same time in liquid fuels and thus, for example, finely divided wood charcoal can be used in addition to amorphous carbon.

As the dispersing medium, known fuels and especially petroleum or products obtained from it such as benzine and the like and benzene or alcohols such as butyl alcohol can also be used.

Furfural can also be used as a dispersing medium, which according to earlier researches of the inventor, can be used for the driving of internal combustion engines.

Lastly, mixtures of fuels can be used such as benzine-benzene mixtures, mixtures of benzine, benzene and furfural or mixtures of benzine, benzene and alcohol.

If necessary, small amounts of materials for increasing the stability of colloidal systems can be added in the known manner to the mixtures.

The fuel mixtures according to the invention which may contain very substantial amounts of products rich in carbon, for example, 25-50% or more of the mixtures, can be used in any way in which the usual fuels are used. In general, it is not necessary to make any alterations to the burning devices such as burners, carburetors and the like.

Example

1. Equal volumes of benzine and benzene are mixed and 25, 30 or if need be up to 50% or more of colloidal carbon is suspended in this mixture, the calorific value of which is to be raised.

2. Equal volumes of benzine and benzene are mixed, one volume of furfural added to this mixture and again 25, 30 or if need be up to 50%

or more of colloidal carbon is suspended in the mixture.

3. To a mixture of 3 parts by volume of benzine and three parts of benzene, one part of butyl alcohol is added which, for example, has been obtained from glucose and 25, 30 or if need be up to 50% or more of colloidal carbon is again suspended in the mixture.

I claim:

10 1. A liquid fuel suitable for use in internal combustion engines, consisting essentially of fur-

furol and a colloidal, substantially pure amorphous carbon obtained by the dry distillation of lignin, dispersed and suspended therein.

2. A method of increasing the calorific value of liquid fuels, which comprises forming a pure amorphous carbon by the dry distillation of lignin, and incorporating such amorphous carbon in finely divided form in a liquid hydrocarbon fuel containing furfurol.

ALEXANDER CLASSEN.
